EVAPORATIVE CABINET AND BLOWER UNIT FOR AUTOMOTIVE AIR CONDITIONERS

William E. Anglin, Dallas, Tex.

Application December 17, 1958, Serial No. 53,808

Term of patent 3½ years

(Cl. D14—6)

Fig. 1

Fig. 2

Fig. 3

Figure 1 is a front left perspective view of the evaporative cabinet and blower unit for automotive air conditioners embodying my new design;

Figure 2 is a front right perspective view of the evaporative cabinet and blower unit for automotive air conditioners; and

Figure 3 is a rear perspective view of the evaporative cabinet and blower unit for automotive air conditioners.

I claim:

The ornamental design for an evaporative cabinet and blower unit for automotive air conditioners, substantially as shown.
